BOX MAKING MACHINE

Alfred L. Rosenmund, Woodport, N. J., assignor
to Stapling Machines Co., a corporation of Del-
aware

Application June 4, 1941, Serial No. 396,509

12 Claims. (Cl. 1—8.2)

This invention relates to machines for making boxes and crates and particularly to machines for making wirebound boxes and crates.

It is an object of the invention to provide certain improvements in the machine shown and described in my pending application Serial Number 349,100, filed August 1, 1940, whereby the efficiency of said machine may be increased and the quality of its product improved.

Specifically the invention is intended to provide means for reducing the crumpling or buckling of the staples and for locating more accurately the staples in the work, means to improve the anchorage of the staple legs in the work, and means automatically to stop the machine when it is subjected to an overload.

One illustrative embodiment of the invention is shown in the accompanying drawings, in which:

Figure 1 is a side elevation of a portion of the rear or delivery end of a machine embodying the invention, certain parts being broken away for clearness of illustration.

Fig. 2 is an enlarged side view of the lower portion of the stapling mechanism shown in Fig. 1, viewed from the opposite side and showing a staple formed and ready to be driven into box parts.

Fig. 3 is an enlarged plan view of the bottom surface of the staple former as seen from the line 3—3 of Fig. 2.

Fig. 4 is an enlarged side view of a portion of the stapling mechanism and the cooperating work support, showing, in broken lines, the position of the staple former and driver prior to a staple driving operation and, in full lines, the position of the staple former and driver at the completion of a staple driving operation.

Fig. 5 is an enlarged perspective view of a staple formed by the stapling mechanism, showing the oppositely-disposed beveled points which cause the staple legs when driven to run in opposite directions.

Fig. 6 is an enlarged diagrammatic view showing, in dotted lines, the direction of travel of the staple legs when the staple is driven vertically downward over a binding wire and into a vertically supported cleat, and showing the tendency of one leg of the staple so driven to deflect toward the side of the cleat and emerge therefrom.

Fig. 7 is a sectional view taken on the line 7—7 of Fig. 4, showing how the work support tilts the cleat at an angle to the vertical to prevent the point of the staple leg from driving through the side of the cleat.

Fig. 8 is an enlarged diagrammatic view somewhat similar to Fig. 7, showing how the point of a staple leg would be driven through the side of a vertically-positioned cleat (shown in broken lines) and how the staple points would be confined within a cleat positioned at the proper angle to the vertical (shown in full lines).

Fig. 9 is a fragmentary transverse sectional view of the work conveyors and work supports viewed from the right in Fig. 1, showing how the work supports at either side of the machine tilt the cleats at an angle to the vertical during a staple driving operation.

Fig. 10 is an enlarged side elevation of a portion of the rear end of the machine showing the automatic overload release or safety device with its parts in operative position, causing the machine to cease operating.

Fig. 11 is a top plan view of the same.

Fig. 12 is the wiring diagram control circuit shown in my application Serial Number 349,100, with the electrical control circuit for the overload release or safety device added.

In the machine of my said pending application Serial Number 349,100, the box parts, usually comprising cleats and superimposed sheets of thin side material, are fed by a continuously moving conveyor to staple forming and driving units which contact the moving work and move therewith during a staple driving operation. The operation of the stapling units is controlled to locate the staples at predetermined selected points in the work. Said machine is provided with an automatically adjustable work support located directly beneath each stapler unit to properly position and support the work during each staple driving operation. Reference is hereby made to said pending application for a detailed description of said mechanisms and the operations thereof.

In the machine of said pending application, the staple former on its downward reciprocating movement contacts the moving work and by frictional engagement therewith is moved with the work just prior to and during a staple driving operation. Such a frictional engagement permits occasional slippage between the staple former and the work, with a resulting defective or inaccurate stapling operation. The present invention provides a positive engagement of the staple former with the work just prior to and during a staple driving operation, to prevent any slippage or relative movement between the work and the staple former during this critical period of time.

In the machine of said pending application, the automatically adjustable work support for the cleats has a horizontal supporting surface and so supports the cleats in a vertical position. When a cleat is so supported, one leg of each staple driven over a binding wire positioned along the center line of the cleat has a tendency to run out a side of the cleat. In the present invention, the work support is provided with a supporting surface at an angle to the horizontal so that the cleat is positioned at an angle to the vertical during a staple driving operation, and such positioning tends to prevent either leg of the staple from running out at a cleat side.

In the machine of said pending application, machine parts are occasionally damaged or broken when the machine jams under an overload. The present invention provides an automatic safety or overload device to stop the machine when for any reason it is overloaded unduly.

The improvements referred to will now be described in the order mentioned.

Means for positively engaging the staple former and the moving work

A staple forming and driving unit is shown at the upper right-hand corner of Fig. 1. A staple former 1 equipped with means for positively engaging the moving work is best shown in Figs. 2, 3, and 4. As there shown, the staple former 1 is recessed at 2 to receive the nut or head 3 of a bolt 4 threaded into a hole in the staple former. The nut 3 is of such thickness as to be substantially flush with the bottom surface of the staple former 1 and has depending therefrom a cone-shaped member or pin 5 extending below the bottom surface of the staple former, to be driven into the upper surface of the work, on the down stroke of the staple former, and thus to lock the staple former and the work against relative movement. As shown by dot-and-dash lines in Fig. 4, the pin 5 enters the box part just prior to a staple driving operation and, as shown by full lines, moves the staple former with the work during the staple driving operation. The elimination of relative movement between the staple former and the work during a staple driving operation reduces the tendency of the staple to crumple or buckle. It should also be noted that the positive engagement between the staple former and the work renders an accurate vertical adjustment of the staple former unnecessary and permits a reduction in the pressure of the staple former on the work, thus reducing the load on the machine.

Work support and positioner

As best shown in Figs. 5 to 9 inclusive, the work support 6 has its upper surface beveled at an angle to the horizontal, as at 7, to tilt the cleat at an angle to the vertical just prior to and during the driving of the staple. Such a tilting reduces the tendency of the staple legs to run out at one side of the cleat, as now explained.

Fig. 6 illustrates the tendency of one staple leg to run out at the side of a cleat when the staple is driven into a vertically positioned cleat. In said figure, the cleat designated 12 is moving in the direction of the arrow. The staple 10 is driven over a binding wire 11, and, when the staple legs enter the cleat, the forward leg 8 and the trailing leg 9 are deflected as shown. Because the forward leg 8 is deflected in the

direction of movement of the cleat 12, it does not run out at the cleat side. The trailing leg 9, however, being deflected against the movement of the cleat 12, frequently runs out at the cleat side, as shown in Fig. 6. Fig. 8 shows this tendency of one leg of the staple to run out at a cleat side when driven into a vertically positioned cleat, as shown in dot-and-dash lines in said figure. The same figure shows how this tendency is reduced when the staple is driven into a cleat positioned at an angle to the vertical, as shown in full lines in said figure. As shown in said figure, when the beveled portion 7 of the support 6 contacts the cleat 12, it tilts the cleat at an angle to the vertical and thereby moves the lower portion of the cleat to the right and increases the amount of cleat material the staple leg 9 must pass through before running out at the side of the cleat.

Since the staples 10 are driven at the same angle relative to the binding wire at each side of the machine, it is necessary that both the left and the right cleats 12 be similarly tilted, as shown in Fig. 9.

The flexing quality of the thin box side material permits a tilting of the cleats in the manner described.

The work support 6 is raised just prior to each staple driving operation to force the upper surface of the box parts into contact with the casting of the stapler unit and is supported in raised position and moves with the work during the stapling operation, all as shown and described in my said application Serial Number 349,100. During this raising and positioning movement of the work support 6, the beveled surface 7 of the present invention tilts the cleat 12 at an angle to the vertical.

Overload release

Figs. 1, 10, and 11 show the drive mechanisms for the machine of said application Serial Number 349,100, with the overload release of the present invention applied thereto.

A main drive sheave 15, rotatably mounted on a main shaft 27, is driven from a motor 13, by belts 14. The stapler units are operated from shaft 27 when drive sheave 15 is clutched to shaft 21, all as described in said application Serial Number 349,100.

The work conveyors 26, trained over sprocket wheels 25 fast on a shaft 24, are moved in the direction of the arrow in Figs. 1 and 10 by a train of mechanisms connecting a sprocket 16 on the hub of drive sheave 15 to a sprocket 23 fast on shaft 24, as best shown in Fig. 1. Such train of mechanisms comprises a chain 17 connecting sprocket 16 to a sprocket 18 on a shaft 19, a series of gears connecting shaft 19 to a shaft 20, and a chain 22 connecting a sprocket 21 on shaft 20 to a sprocket 23 on shaft 24. The starting and stopping of work conveyors 26 is controlled by a clutch interposed between sprocket 18 and shaft 19, all as described in said application Serial Number 349,100, reference to which is made for a detailed description of the mechanisms for operating the stapler units and the work conveyors.

In the machine of the said application, when the clutched conveyor drive sprocket 18 was submitted to an undue overload, such as, for instance, might possibly be caused by a cleat being caught between the under surface of the conveyor band 26 and the face of the conveyor band sprocket 25, causing an excessive load or

perhaps jamming the conveyer mechanism, the clutch housed within the conveyer drive sprocket 18 would slip, eliminating any severe damage to the conveyer mechanism, but permitting serious damage to the staple former-driver unit. For example: It is a normal condition to have the main drive sheave 15 rotate at 300 revolutions per minute, and with the main shaft 27 clutched thereto, each revolution is also a cycle of operation of the staplers, during which a staple 10 is formed and driven. Thus, 300 staples are driven per minute. Any hesitation or stopping of the conveyer bands 26 permits the driving of a considerable number of staples at one point in the box material. This condition causes serious damage to the staple outlet portion of the vertical internal grooves of the staple former 1, to the driving portion of the driver member, and to other stapler elements.

The automatic overload device of this invention stops the conveyer band mechanism and the stapler mechanism when the load on the driven conveyer mechanism exceeds a predetermined safe load, thus eliminating the damage mentioned above.

As best shown in Figs. 10 and 11, there is fastened to a machine frame member 29, a depending plate 28 having a bore 30 adjacent its lower extremity. Loosely journaled in the bore 30 is a shaft 31 having secured on its innermost end an arm 32 which accommodates a stud 33 which has rotatably mounted thereon an idler sprocket 34. At its other end, shaft 31 carries an arm 35 extending upwardly adjacent the outside surface of the plate 28 at a predetermined angle with the arm 32. The arm 35 is continually urged toward a stop member 36 by the action of a tension spring 37 which has one of its ends fastened to the uppermost portion of the arm 35 and its other end fastened to an adjustable anchor 38. The adjustable anchor 38 is slidably mounted horizontally in a support block 39 carried by arms 58 permanently secured to the plate 28. Threaded on the end portion of the adjustable anchor 38 which extends beyond the support block 39, are a pair of lock nuts 40 which provide an adjusting means whereby the length of the adjustable anchor 38 may be varied as desired, thus increasing or decreasing the load on the tension spring 37. The arm 35 has threaded through its upper portion, parallel to the plate 28, an adjustable stud 41 accommodating a locking element. The stud 41, located on the arm 35, will actuate an electric switch 42 fastened to the outside surface of the plate 28 when the arm 35 is moved from left to right.

The operation of this device as an automatic overload release is as follows: The drive chain 22, having a sufficient amount of slack purposely allowed, is trained about the sprockets 21 and 23 with its driving side 44 trained over the uppermost teeth of the idler sprocket 34, as illustrated in Figs. 1, 10, and 11. The tension on the driving side 44 of the drive chain 22, when the machine is in operation, tends to produce a downward force upon the idler sprocket 34 and to straighten out the driving side 44 of the drive chain 22. This is counteracted by the pull of the tension spring 37 on the upwardly extending arm 35. The proper setting of the tension spring 37 to counteract the downward force of the driving side 44 of the drive chain 22 under a predetermined safe driving load can be determined, since the downward force of the driving side 44 of the drive chain 22 is propor-

tional to the driving load along the driving side 44 of the drive chain 22, as shown in Fig. 1. Should the load on the conveyer drive sprocket 18 increase above the predetermined safe load and jam the machine, the tension in the driving side 44 of the drive chain 22 increases, thus increasing the downward force on the idler sprocket 34 above the predetermined counteractive force of the tension spring 37, which causes the shaft 31 to rock clockwise to move the upwardly extending arm 35 from the left or normal position (Fig. 1) to the right to bring the adjustable stud 41 in contact with and to open the normally-closed electric switch 42, which immediately causes the driving mechanisms of both the conveyer bands 26 and the staplers to cease instantly, thus safeguarding the conveyer bands 26 and their relative driving mechanism and preventing any serious damage to the staple former-driver units. After the cause of jamming the machine has been corrected, the electric switch 42 is reset manually by the push button 43.

Fig. 12 shows a diagram of the electrical control circuit of the machine of my application Serial Number 349,100, and, added thereto, the electrical circuit of the overload release device. The conveyers 26 are set in motion by the clutching of the conveyer drive sprocket 18 to the conveyer drive shaft 19 and of other co-acting mechanism to the conveyer band sprockets 25, through the energizing of a conveyer clutch solenoid 45. This is caused by moving a handle 46 of an operator's control switch 47 to the starting position, which closes a contact 48. This energizes a solenoid contactor 49 by allowing current to pass through a magnetic coil 50 and closes contacts 51 and 52 while at the same time opening contact 53. Current passes through contact 52 to energize the conveyer clutch solenoid 45, which disengages a conveyer clutch brake 56 against the action of a brake spring 57. Opening the contact 53 leaves a main clutch solenoid 54 free to act in accordance with the action of a switch 55, which controls the operation of the stapling mechanism. The overload release switch 42 is normally closed and is in the line of magnetic coil 50 and starting contact 48 of the operator's control switch 47. When the conveyer bands 26 are subjected to a load beyond the predetermined safe load, the overload release switch 42 will be actuated by the adjustable stud 41 of the upwardly-extending arm 35. With contact broken in the overload release switch 42 (which must be reset manually) current ceases to pass through the magnetic coil 50, which deenergizes the solenoid contactor 49 and opens the contacts 51 and 52 while at the same time closing contact 53. When current ceases to flow through the contact 52, the conveyer clutch solenoid 45 is deenergized, which permits the brake spring 57 to apply the conveyer clutch brake 56 to disengage the clutch from the conveyer drive sprocket 18. Current, passing through contact 53, which is closed, energizes the main clutch solenoid 54 and stops rotation of the main shaft 27 and the stapler mechanism as well, by declutching the main drive sheave 15. The result is equivalent to moving the handle 46 of the operator's control switch 47 to stop position, which means that no current passes through the contact 48 of the operator's control switch 47. All operating mechanisms of the machine are now at rest, excepting the main drive sheave 15 and conveyer drive sprocket 18.

until the push button 43 of the overload release switch 42 is reset after the cause of the overload has been eliminated.

Among other advantages, the machine of this invention produces a better product and reduces machine upkeep costs.

It will be understood that the invention is not to be limited to the specific embodiment shown herein for illustration and that all of the features of the invention need not be used conjointly, as they may be used to advantage in various combinations as defined in the claims.

I claim:

1. In a box-part stapling machine having means to move box parts and having staple forming and driving mechanism movable with the box parts during a staple driving operation, a staple former provided with a pointed projection adapted to be driven into a box part to lock the staple former and the box part against relative movement during a staple driving operation.

2. In a box-part stapling machine having means to move box parts and having staple forming and driving mechanism movable with the box parts during a staple driving operation, a staple former provided with a pin adapted to be driven into a box part to lock the staple former and the box part against relative movement during a staple driving operation.

3. In a box-part stapling machine having means to move box parts and having staple forming and driving mechanism movable with the box parts during a staple driving operation, a staple former provided with means adapted to be driven into a box part to lock the staple former and the box part against relative movement during a staple driving operation.

4. In a box-part stapling machine having means to move box parts and having staple forming and driving mechanism movable with the box parts during a staple driving operation, an automatically adjustable work support provided with a beveled supporting surface adapted to tilt a box part at an angle to the vertical and to hold it in such tilted position during a staple driving operation.

5. In a box-part stapling machine having means to move box parts and having staple forming and driving mechanism movable with the box parts during a staple driving operation, a staple former provided with means adapted to be driven into a box part to lock the staple former and the box part against relative movement during a staple driving operation, and an automatically adjustable work support provided with a beveled supporting surface adapted to tilt the box part at an angle to the vertical and to hold it in such tilted position during a staple driving operation.

6. In a box-part stapling machine having

means to move box parts and having staple forming and driving mechanism movable with the box parts during a staple driving operation, a staple former provided with means to lock the staple former and the box part against relative movement during a staple driving operation.

7. In a box-part stapling machine having means to move box parts and having staple forming and driving mechanism movable with the box parts during a staple driving operation, a staple former provided with means to prevent the staple former from slipping on the moving box part during a staple driving operation.

8. In a box-part stapling machine having means to move box parts and having staple forming and driving mechanism movable with the box parts during a staple driving operation, means to lock the staple former and the box part against relative movement during a staple driving operation.

9. In a box-part stapling machine having means to move box parts and having staple forming and driving mechanism movable with the box parts during a staple driving operation, means to prevent the staple former from slipping on the moving box part during a staple driving operation.

10. In a box-part stapling machine having a drive shaft, a drive sheave rotatably mounted on the drive shaft, means to clutch the drive sheave to the drive shaft to rotate the drive shaft, a conveyer for the box parts, and stapling mechanism operable upon rotation of the drive shaft: a safety device comprising means automatically to break the clutching engagement between the drive sheave and the drive shaft when the machine is subjected to a predetermined overload.

11. In a box-part stapling machine having a drive shaft, a drive sheave rotatably mounted on the drive shaft, means to clutch the drive sheave to the drive shaft to rotate the drive shaft, a conveyer for the box parts, and stapling mechanism operable upon rotation of the drive shaft: a safety device comprising electrically operable means automatically to break the clutching engagement between the drive sheave and the drive shaft when the machine is subjected to a predetermined overload.

12. In a box-part stapling machine having a drive shaft, a drive sheave rotatably mounted on the drive shaft, means to clutch the drive sheave to the drive shaft to rotate the drive shaft, a conveyer for the box parts, and stapling mechanism operable upon rotation of the drive shaft: a safety device comprising means controlled by the load on the conveyer to break the clutching engagement between the drive sheave and the drive shaft.

ALFRED L. ROSEN MUND.
